GASEOUS ELECTRIC DISCHARGE DEVICE

Hans Alterthum and Marcello Pirani, Berlin-Wilmersdorf, Germany, assignors to General Electric Company, a corporation of New York

Application December 2, 1936, Serial No. 113,919
In Germany December 6, 1935

3 Claims. (Cl. 176—124)

The present invention relates to gaseous electric discharge devices generally and more particularly the invention relates to such devices useful as light sources and for advertising.

5 The object of the invention is to provide a gaseous electric discharge lamp outfit for operation on commercial sources of symmetrical alternating current which outfit comprises a gaseous electric discharge device emitting different colored light 10 from different parts thereof and which is useful in the advertising and illumination fields. Still further objects and advantages attaching to the device and to its use and operation will be apparent to those skilled in the art from the following particular description.

A gaseous electric discharge device having a mixture of gases therein, which gases have different ionizing potentials, emits different colored light from different parts thereof when the device 20 is operated on direct current since the gas having a lower ionizing potential travels toward the cathode and the gas having the higher ionizing potential travels toward the anode under the influence of the direct current discharge. This 25 separation of the gases is known in the art as electrophoresis and in pronounced cases in discharge devices having an elongated tubular container the tube has the appearance of two linear luminescent columns of different color, for example, when a mixture of neon and argon is used 30 in the tube the device appears red at one end thereof and blue-violet at the other end thereof. When such devices are operated on symmetrical alternating current this phenomena does not take 35 place because the tendency of the gases to separate during one half cycle is overcome by the reversal of current flow in the next half cycle. It is, of course, possible to cause the separation of the gases in an alternating current device by superimposing a direct current on the alternating current, but such an apparatus is expensive and 40 complicated.

The present invention attains its objects by transforming in the lamp itself a symmetrical 45 alternating current supplied to the discharge device into an unsymmetrical alternating current to a degree that separation of the constituents of the gas mixture takes place with the effect described above. The transforming of the symmetrical alternating current supplied to the tube into unsymmetrical alternating current can be accomplished in many different ways, for example, when thermionic electrodes are used the electrode at one end of the tubular container has a 50 different electron emissive capacity than that of

the electrode at the other end of the tube; or when cold electrodes are used one electrode is activated and the other is not, or when cold electrodes of equal size are used in each end of the tube the tube is connected across a high voltage 5 transformer which has an operating voltage slightly greater than the starting voltage of the tube and a particularly sensitive part of the tube is grounded. The sensitive part of the tube is discovered by groping either with the bare hand 10 or with a grounded band. The assymmetry of the alternating current is equivalent to the superimposing of a direct current on the alternating current applied to the tube and has a like effect, that is, it causes the separation of the constituents 15 of the gas mixture so that one end of the tube emits a light typical of the gas collected thereat and the other end of the tube emits light typical of the different gas collected thereat.

It is sufficient for the purpose of the invention 20 if the separation of the gases in the tube proceeds only to that point whereat the gas having the lower ionizing potential is moved out of one part of the tube. Since the gas having the higher ionizing potential is excited to luminescence by 25 the discharge only in that part of the tube containing very little of the gas having the lower ionizing potential the tube then emits different colored light from different parts thereof.

Preferably the tubular container of the device 30 is many times greater in length than in diameter and the diameter itself is preferably small. The thermal diffusion of the gases in the tube, which tends to overcome the separation of the gases under the influence of the unsymmetrical alternating current, is thus minimized. Preferably the percentage of gas having the lower ionizing potential, for example, argon in an argon helium mixture, or mercury in a neon mercury mixture, is such that it is just sufficient to emit light. We 40 have observed that the smaller the amount of the component having the lower ionizing potential the faster is the separation of the gases in the tube.

In the drawing accompanying and forming part 45 of this specification two embodiments of the invention are shown, in which

Fig. 1 is a side elevational view of one embodiment of the invention, and

Fig. 2 is a similar view of another embodiment 50 of the invention.

Referring to Fig. 1 of the drawing the gaseous electric discharge device comprises a tubular container 1 having electrodes 2 and 3 sealed therein at the ends thereof and having a gaseous atmos- 55

phere therein. Said electrodes 2 and 3 are electron emitting when heated to an elevated temperature by the effects of the discharge incident thereto and consist of a pellet of electron emitting material, such as barium oxide, having a filament of high melting point material, such as tungsten, wrapped around said pellet. The electrodes 2 and 3 are selected so as to have different electron emissive capacity. The gaseous atmosphere 10 consists of a mixture of helium at a pressure of approximately 6.7 mm. and argon at a pressure of approximately 0.3 mm. The tubular container 1 is about 7 mm. in diameter and the electrodes 2, 3 are separated a distance of about 15 300 mm. When the lamp described above is connected to a source of symmetrical alternating current a visible separation of the gas mixture takes place immediately after the discharge has started and the maximum separation of the constituents takes place in approximately 30 seconds. The discharge in the end of the tube whereat the less emissive electrode is mounted appears yellow-rose in color and the discharge at the opposite end of the tube appears blue-violet in color. 20 25 A tube having this appearance is, of course, useful for advertising purposes.

When cold electrodes 5 and 6 are used a sensitive part of the container 1 is connected to ground by band 7, as shown in Fig. 2 of the drawing, and as disclosed above.

When the gaseous atmosphere comprises a metal vapor and a fixed gas, such as a mixture of neon and mercury vapor, a similar separation takes place, the blue colored light from the mercury vapor being present at the electrode having the smaller cathode drop and the red neon light appearing at the electrode with the larger cathode drop. In this case it is advantageous to place the source of the mercury vapor at that end 35 40 of the tube to which the vapor travels during the operation of the tube. This is accomplished in many different ways, for example, an offset chamber mounted at the desired part of the tube is particularly effective. Preferably, however, 45 the quantity of vaporizable mercury in the tube is such that it is completely vaporized during the operation thereof.

When desired, a light approximating white light can be obtained from a device similar to the device described above when the container 1 is filled 50 with mercury vapor and contains neon at a pressure of approximately 2 mm. In this case the tube is preferably surrounded by a light diffusing jacket which mixes the red and the blue light emitted from different parts of the tube. In this 55 case the container 1 is preferably of U-shape or is coiled helically. When desired, sodium is introduced into the tubular lamp container of the above embodiment and the light from the sodium 60 is visible at the cathode having the smallest drop, the blue light of the mercury is visible in the center portion of the tube and a red luminescent neon light is visible adjacent the other electrode.

While we have shown and described and have 65 pointed out in the annexed claims certain novel features of the invention, it will be understood that various omissions, substitutions and changes in the forms and details of the device illustrated and in its use and operation may be made by

those skilled in the art without departing from the broad spirit and scope of the invention, for example, when deaerated fluorescent material is applied to the tubular container which material emits light different in color than the light 5 emitted by any of the gases in the tube, when desired, a yellow fluorescent material, such as zinc silicate, is applied to that part of the wall of the container surrounding the luminous mercury column of a device containing neon and mercury 10 vapor to obtain a light approximating white light.

What we claim as new and desire to secure by Letters Patent of the United States, is:—

1. In combination a current source of symmetrical alternating current, a gaseous electric 15 discharge device connected across the terminals of said source, said device comprising an elongated tubular container, electrodes sealed therein at the ends thereof, a mixture of gases therein each of said gases having a different ionizing 20 potential said electrodes being cold electrodes, the voltage of said current source being slightly higher than the starting voltage of said device, a sensitive part of said device being grounded to transform the symmetrical alternating current 25 into unsymmetrical alternating current in said device to cause said device to emit different colored light from different parts thereof.

2. In combination a current source of symmetrical alternating current, a gaseous electric 30 discharge device connected across the terminals of said source, said device comprising an elongated tubular container, electrodes sealed therein at the ends thereof, a mixture of gases therein, each of said gases having a different ionizing 35 potential said electrodes being cold electrodes, the voltage of said current source being slightly higher than the starting voltage of said device, a sensitive part of said device being grounded to transform the symmetrical alternating current 40 into unsymmetrical alternating current in said device to cause the discharge in said device to emit different colored light from different parts thereof and a luminescent material capable of 45 light emission under irradiation by said discharge mounted in light receiving relation to said discharge.

3. In combination a current source of symmetrical alternating current, a gaseous electric discharge device connected across the terminals 50 of said source, said device comprising an elongated tubular container, electrodes sealed therein at the ends thereof, a mixture of argon and mercury vapor therein, each of said gases having a different ionizing potential said electrodes being 55 cold electrodes, the voltage of said current source being slightly higher than the starting voltage of said device, a sensitive part of said device being grounded to transform the symmetrical alternating 60 current into unsymmetrical alternating current in said device to cause the discharge in said device to emit different colored light from different parts thereof and a luminescent material capable of light emission under irradiation by 65 said discharge mounted in light receiving relation to said discharge.
